DETACHABLE BLADE POCKETKNIFE

Thomas R. Arden, Danbury, Conn., assignor to
 Bard-Parker Company, Inc., Danbury, Conn.,
 a corporation of New York

Application March 7, 1951, Serial No. 214,275

2 Claims. (Cl. 30—156)

1

This invention relates to pocket knives of the type comprising a handle and a removable, replaceable blade which is pivoted to the handle for swinging movements between a closed position in which it is housed in and protected by the handle, and an open position in which it extends from the front end of the handle substantially in alinement with the latter.

According to the invention there is pivoted to the front end of the housing a shank by which the blade is carried, and in this connection an object of the invention is to provide for mounting the blade on said shank in a simple, firm and practical manner such that it may readily and easily be removed and replaced whenever desired.

The blade is of the thin, laterally flexible type in order that it may be removably, replaceably mounted on the shank in accordance with the invention, and in this connection another object of the invention is to provide said blade along its back edge with a stiffening flange or flanges extending laterally from one or both sides of the blade and to mount the blade so that when it is closed and protectively disposed in the handle said flange or flanges is or are disposed in part slightly outwardly with respect to the open edge of the handle for finger nail engagement to facilitate initial swinging movement of the blade from its closed toward its open position.

With the foregoing and other objects in view, as will become more fully apparent as the nature of the invention is better understood, the same consists in a pocket knife of the removable, replaceable blade type embodying the novel features of construction, combination and arrangement of parts as are illustrated by way of example in the accompanying drawing and as will be hereinafter more fully described and claimed.

In the accompanying drawing, wherein like characters of reference denote corresponding parts in the different views:

Figure 1 is a side elevation of a pocket knife constructed in accordance with the invention and shown in closed condition.

Figure 2 is a longitudinal section through the knife as shown in Figure 1.

Figure 3 is a longitudinal section through the knife with the blade in its open position relative to the handle.

Figure 4 is an elevation of the knife with the blade in open position and looking toward the open edge of the handle.

Figure 5 is a side elevation of the blade and the shank of the knife in separated relationship to each other; and

2

Figure 6 is a cross section on the line 6—6 of Figure 2.

Referring to the drawing in detail, A designates generally, the handle of the present knife; B designates, generally, the knife blade, and C designates, generally, a shank which is pivoted to the handle A and upon which the blade B is removably, replaceably mounted.

The handle A is composed of a pair of side plates 10, 10 and an interposed leaf spring 11 against the sides of which said side plates are suitably secured, as for example, by means of rivets 12.

The leaf spring 11 extends contiguously to the back edges of the side plates 10, 10 substantially from end to end of the latter and serves to space said side plates apart as well as to serve as a closure at the back edge of the handle for the space between said side plates, which space is open at the front edge of the handle as shown.

Only the rear end portions of the side plates 10, 10 and the leaf spring 11 are secured together so as to leave the front end portion of said leaf spring free for backward and forward flexure.

The inner end portion of the shank C is of block-like form and is interposed between the front end portions of the side plates 10, 10 and is pivotally secured to said side plates by a rivet 13 for swinging movement through an angle of substantially 180° between a closed position in which it extends substantially longitudinally of the handle A between the side plates 10, 10 thereof, as illustrated in Figure 2 and an open position in which it extends substantially longitudinally with respect to said handle forwardly beyond the front end of the latter.

The front end portion of the leaf spring 11 cooperates with flat front and rear edges of the block-like inner end portion of the shank C to yieldably hold said shank in its aforesaid closed and open positions, respectively, and a shoulder 14 is provided on the said inner end portion of said shank to engage the front end of the leaf spring 11 when said shank is in its open position to positively prevent it from swinging beyond its said open position.

The shank C is of narrow, elongated form and at one side thereof, adjacent to the block-like inner end portion thereof, is recessed to provide an inwardly facing shoulder 15 and, inwardly of shoulder, a side surface 16 which, as shown in Figure 4, is gradually curved laterally outward as it extends inwardly from said shoulder.

In the front and rear edges of the shank C and extending from the outer end thereof suit-

able distances inwardly therealong are channels 17, 17 which are alined with the outer end portion of the side face 16 of said shank.

The blade B is thin and at least the inner end portion thereof is laterally flexible. In said blade and extending longitudinally thereof is an elongated slot 18 the inner end portion of which is of a width corresponding to the width of the outer end portion of the shank C and the outer end portion of which is of a width corresponding to the distance between the bottoms of the channels 17, 17. The length of said slot 18 is approximately equal to the distance between the outer end of the shank C and its shoulder 15.

From the foregoing it will be apparent that the blade B may readily and easily be mounted securely and firmly on the shank C simply by first entering the outer end of said shank in the inner end portion of the slot 18 and thereafter alining the portions of the blade B at both sides of the outer end portion of the slot 18 with the channels 17, 17, and then, as permitted by the flexibility of the blade, sliding the blade inwardly relative to said shank until the inner end of the slot 18 engages behind the shoulder 15. As the blade is slid inwardly relative to the shank C the blade portions at both sides of the outer end portion of the slot 18 enter the channels 17, 17 and thus secure the blade against both lateral movement and movement in its plane relative to said shank, while by engagement of the portions of the blade at the inner and outer ends of the slot 18 behind the shoulder 15 and against the outer end of the shank, respectively, the blade is effectively secured against endwise movement relative to the shank. Due to the curvature of the side face 16 of the shank C against which the inner end portion of the blade B rests when said blade is applied to said shank, the said inner end portion of said blade is maintained under lateral flexure so that any looseness of the blade with respect to the shank is avoided.

To remove the blade from the shank the inner end portion of the blade simply is flexed laterally to disengage the portion thereof at the inner end of the slot 18 from behind the shoulder 15, whereupon the blade is free to be shifted outwardly along and to be disengaged from the shank.

Extending along the back marginal portion and laterally outward from one or both sides of the blade B is a blade stiffening and reinforcing rib or ribs 19 as desired. In either case it is a feature of the invention that when the blade is mounted on the shank C its disposition relative to said shank is such that when the shank and the blade are in their closed positions, as shown in Figures 1, 2 and 6, at least the outer end portion or portions of the rib or ribs 19 is or are disposed outwardly with respect to the open edge of the handle A for finger nail engagement to facilitate initial opening swinging movement of the blade and shank from the handle A.

Preferably, but not necessarily, the handle side plates 10, 10 are provided along their front edges with outwardly extending stiffening ribs 20, while optionally the handle A may or may not be pro-

vided at its rear end with a clevis 21 by means of which a chain may be attached to the knife if desired.

From the foregoing description considered in connection with the accompanying drawing it is believed that the construction and operation of the present knife will be clearly understood and its advantages appreciated. It is desired to point out, however, that while only a simple, specific structural form of the knife has been illustrated and described, the same is readily capable of specifically different structural forms within the spirit and scope of the invention as defined in the appended claims.

I claim:

1. A pocket knife comprising a handle, a shank pivoted at one end to said handle for swinging movements between open and closed positions relative thereto, said shank at one face thereof and near its pivoted end being recessed and thereby being provided with an inwardly facing shoulder at the outer end of said recess, said shank outwardly of said recess being of substantially uniform thickness from face to face and the upper and lower edges of said shank outwardly of said shoulder being substantially parallel, said edges having therein channels which extend longitudinally of said shank and which are alined with the face of said recess, said channels opening through the outer end of said shank and having their inner ends terminating outwardly of said shoulder, a thin, laterally flexible, normally flat blade having therein a longitudinally extending slot the outer end portion of which is of a width approximately equal to the distance between the bottoms of the channels in said shank, said blade-slot being otherwise of approximately the same size and shape as said shank outwardly of said shoulder, whereby it is engageable and interlockable with said shank by sliding the same rearwardly relative to said shank under lateral flexure to engage portions thereof at both sides of the slot therein with the grooves of said shank and to engage the portion thereof at the rear end of the slot therein behind said shoulder.

2. A pocket knife as set forth in claim 1 in which the recessed portion of the shank has a laterally rearwardly and outwardly inclined face to maintain the end portion of the blade nearer the handle under lateral flexure when said blade is interlocked with said shank, thereby to avoid any looseness between said blade and said shank.

THOMAS R. ARDEN.
